UNITED STATES PATENT OFFICE.

JAMES F. GOUNLEY, OF PHILADELPHIA, PENNSYLVANIA, ASSIGNOR TO ROYAL ELECTROTYPE COMPANY, A CORPORATION OF PENNSYLVANIA.

BLACKLEADING-MACHINE.

1,134,606.

Specification of Letters Patent.

Patented Apr. 6, 1915.

Application filed November 18, 1911. Serial No. 660,978.

To all whom it may concern:

Be it known that I, JAMES F. GOUNLEY, a citizen of the United States, and a resident of Philadelphia, county of Philadelphia, 5 and State of Pennsylvania, have invented certain new and useful Improvements in Blackleading-Machines, whereof the following is a specification, reference being had to the accompanying drawings.

10 This invention particularly relates to machines of the class by which matrices of the like are coated by spraying with a graphite laden liquid.

It is well known in the art of liquid coating to provide a reciprocatory table or carrier for matrices, whereby they are reciprocated in a bath of graphite laden liquid beneath a transversely disposed slotted pipe or nozzle, which directs said liquid in a transverse line. This method has been found to be inefficient, as it not only requires considerable time to separately coat each matrix, but also permits sediment, comprising the suspended particles of graphite, to lodge or 25 collect in the angles at the bottom of the type impressions, in that portion of the matrix which is submerged and which is not being acted upon by the stream of liquid under pressure. By reason of the lodgment 30 of the particles of suspended graphite, the graphite coated matrices are required to be thoroughly rinsed in a separate machine, to dispose of the surplus graphite thus collected, whereby considerable of said graphite 35 is either wasted, or means must be provided for collecting it in a separate receptacle.

The principal object of this invention is to obviate the disadvantages and to eliminate the difficulties found in machines of 40 known construction, and to provide a machine that will not only save the time of the operator, but will more efficiently provide a uniformly thin coating of electrically conductive material upon the articles treated.

45 Other objects of this invention are to provide a machine of the class contemplated, with a continuously progressed conveyer, upon which electroplate matrices may be continuously fed at one end, and progressed 50 at a predetermined speed beneath a series of spraying nozzles, and automatically discharged at the other end.

Further objects of this invention are to provide transversely disposed spraying nozzles having jet apertures radially dis-

posed in regularly spaced transverse planes, to provide said nozzles in such spaced relation that the adjacent jets of the respective nozzles will overlap before impinging upon the articles being treated, to provide the jet apertures of the adjacent nozzles in relatively staggered relation, so that the adjacent sprays of relatively adjacent nozzles will respectively alternate, and to provide agitating nozzles along the bottom of the 60 tank, for agitating the sediment. 65

Briefly stated, this invention includes an elongated tank having a conveyer belt arranged to be progressed with the tank subjacent to a series of suitably disposed parallel transversely extending nozzles which are so disposed with respect to each other as to provide an unbroken discharge upon said belt or carrier throughout nearly its entire extent, means for progressing said conveyer 70 belt at a predetermined speed, and means for drawing liquid from the bottom of said tank and forcing it under pressure through said nozzles. 75

This invention further includes all of the 80 various novel features of construction and arrangement hereinafter more definitely specified.

In the accompanying drawings, Figure 1 is a side elevational view of a machine constructed in accordance with this invention, a portion being broken away and shown in section for convenience of illustration. Fig. 2 is a transverse vertical sectional view of said machine taken on the line 2—2 in Fig. 1, and Fig. 3 is a detached view showing the nozzle *per se*, directing jets of liquid upon a wax matrix, which is shown in section for the convenience of illustrating the action of the spray on the type portion of the 90 matrix, and the impressions formed by said type. 95

In said drawings the tank 5 is supported on suitable legs 6, and comprises the bottom wall 7, which is inclined from the opposite ends of said tank downwardly toward a centrally disposed outlet aperture 8. 100

Journalized in suitable bearings 10 in the side walls of the tank 5 are the rotatable shafts 11 and 12, which respectively carry sprocket 105 wheels 13 and 14. Said sprocket wheels 13 and 14 carry the sprocket chains 15, respectively connected by suitable disposed parallel bars or slats 17, which are progressed by the rotation of said shafts 11 and 12, and 110

form a convenient belt conveyer for the carriage of matrices or the like to be treated.

The driven shaft 11 is provided with a worm gear 20 coöperative with the worm 21, 5 on the shaft 22, which is journaled in bearings in 23 and 24, and which is provided with the driving pulley 25, for connection with any suitable form of motive power.

To each of the side walls of the tank 5 is 10 secured a track rail 28, preferably formed of angle-iron, whose extending horizontal web 29 provides a track upon which the sprocket chains of the conveyer belt 18 rides, and which is slightly bent downwardly at its 15 forward end 30 to facilitate the proper engagement of said chains therewith.

The discharge end wall 32 of the tank 5 terminates short of the upper perimeter of the tank, substantially in a plane with the 20 upper surface of the conveyer 18, and is provided with a suitable outwardly extending shelf 33, supported on brackets 34, upon which shelf the matrices 35 may be automatically discharged from said conveyer 25 belt, and may be conveniently removed therefrom by the operator.

The outlet aperture 8 is conveniently connected by the outlet pipe 40 with the inlet 41 of the centrifugal pump 45, having the 30 shaft 46 provided with the pulley 47 for connection with suitable motive power. The outlet 48 of the centrifugal pump 45 is connected by the pipe 50 with the distributing pipe 52, comprising the T-fittings 53 35 and the L-fittings 55, and supported by the bridge brackets 57, extending from the walls of the tank 5. The fittings 53 and 55 are each provided with laterally extending nozzle sections 60, disposed in parallel relation 40 to each other, and in transverse relation with respect to the travel of the conveyer. Said nozzle sections 60 each comprise a removable lower half section 62 connected with the upper section by bolted flanges 64 and 65, respectively integral with, and circumscribing the perimeters of said sections. Each of the lower half sections 62 of the nozzles are provided with jet outlet apertures, which are disposed radially through the wall of said 50 lower sections 62, in transverse parallel planes equally spaced at suitable distances throughout the longitudinal extent of said nozzles, it being noted that the outlet apertures of the respectively adjacent nozzles 55 are disposed in equally spaced alternate planes, or in other words, in staggered relation, so that the sprays 70 of the nozzle at the receiving end of the machine, alternate with the sprays 71 of the adjacent nozzle, 60 and the sprays 72 of the last mentioned nozzle alternate with the sprays 73 of the next succeeding nozzle, and the sprays 74 of the last mentioned nozzle alternate with the sprays 75 of the next succeeding nozzle at 65 the discharge end of the machine. It may

be here noted that owing to the fact that the graphite is merely held in suspension in the liquid, it is likely to form sediment in the bottom of the tank 5, and therefore the nozzles 80 and 81 are provided near the ends of said tank 5, and extending transversely thereof and having jet outlets for directing agitating jets toward the outlet aperture 8; said nozzle being respectively connected by the pipe 82, with the pressure pipe 50.

It will be seen from the foregoing description, that the relation of the respective nozzles and their respective outlet apertures, is an important factor in the uniform treatment of the matrices carried by the conveyer belt, and that when a matrix is placed upon said conveyer belt, it is continually sprayed during its progression from the receiving end of the machine to the discharging end, and therefore no interruption or intermission in the treatment of the matrix is effected, and the sprays are so directed that every crevice in the matrix receives equal treatment with the prominent portions thereof, and furthermore, by reason of the fact that the spraying action is uninterrupted, the possibility of sediment being lodged in the crevices and caking therein is entirely eliminated, which fact is advantageous, in that little or no rinsing of the treated plate is required when discharged from a machine constructed in accordance with this invention, and therefore waste, by surplus material being lodged in the crevices of the matrix would be impossible.

It is not desired to limit this invention to the precise details of construction and arrangement herein set forth, as various modifications may be made therein, without departing from the essential features and scope of the invention as herein set forth and defined in the appended claims.

Having thus described my invention, I claim:

1. In a machine of the class described, the combination with a conveyer, and a series of spraying nozzles having jet apertures arranged in radial relation to the nozzle axis at suitable intervals, the sprays of one nozzle being directed in alternate relation with the sprays of the adjacent nozzle.

2. In a machine of the class described, the combination with a conveyer, of means to progress said conveyer at a predetermined speed, and a series of spraying nozzles suitably disposed superjacent to said conveyer, and having jet apertures arranged in radial relation to the nozzle axis, in planes spaced at suitable intervals transverse to said axis, the sprays of one nozzle being directed in alternate relation with the sprays of the adjacent nozzle.

3. In a machine of the class described, the combination with a conveyer, of means to progress said conveyer, and a series of

- spraying nozzles operatively disposed with respect to said conveyer and having jet apertures arranged in radial relation to said nozzle axis and arranged to direct sprays in 5 planes spaced at suitable intervals transverse to said axis, the sprays of one nozzle being directed in alternate relation with the sprays of the adjacent nozzle.
4. In a machine of the class described, the 10 combination with a belt conveyer, of means to progress said conveyer at a predetermined speed, and a series of spraying nozzles comprising elongated transversely disposed casings, having jet outlet apertures directed radially in parallel planes, and disposed at suitable distances transverse to the axis of said nozzles, the jet outlets of adjacent nozzles being disposed in relatively staggered relation.
5. In a machine of the class described, the 15 combination with a belt conveyer, of means to progress said conveyer at a predetermined speed, a series of parallel sprayers disposed superjacent to said belt, and having parallel series of jet apertures disposed radially in spaced parallel planes transverse to the axes of said sprayers and respectively directed at different angles to the plane of said conveyer, and means to force graphite laden liquid through said nozzles, upon articles carried by said conveyer, the sprays of adjacent nozzles being directed in staggered relation overlapping, to insure a continuous treatment of said articles.
6. In a machine of the class described, the 20 combination with a belt conveyer, of means to progress said conveyer at a predetermined speed, a series of nozzles suitably supported superjacent to said conveyer, and having jet outlet apertures directed radially in parallel planes extending longitudinally of said conveyer, the respective sprays of adjacent nozzles being directed in 25 staggered relation upon the articles carried by said conveyer, and means arranged to force graphite laden fluid under pressure through said nozzle.
7. In a machine of the class described, the 30 combination with a tank having an electrically conductive material suspended in fluid therein, of a belt conveyer arranged to travel in said tank, and to carry articles to be coated with said electrically conductive material, a series of parallel transversely disposed spraying nozzles suitably supported superjacent to said conveyer each having a plurality of radial series of outlet apertures, the jet outlets of the respective 35 nozzles being arranged to direct sprays of fluid uninterruptedly, at relatively different angles to the surface of said articles throughout their progression through said tank, and means to draw the liquid from the bottom of said tank and direct it under 40 pressure through said nozzles, the sprays of adjacent nozzles being directed to overlap without interfering.
8. In a machine of the class described, the 45 combination with a tank containing an aqueous solution of electrically conductive material, of a belt conveyer arranged to be progressed through said tank, and rotatably supported at its opposite ends, a track intermediate of the ends of said conveyer, operative to prevent sagging, means to progress the conveyer at a predetermined speed, a series of spraying nozzles in suitable spaced superjacent relation with respect to said conveyer, and in transverse relation thereto, each having jet apertures disposed in radial transverse alinement operative to direct sprays upon articles carried by said conveyer, the adjacent jets of respectively adjacent nozzles being arranged to direct sprays in crossed relation before impinging upon said articles and being relatively staggered, and means arranged to draw said liquid from the bottom of said tank and direct it under pressure through said nozzles.
9. In a machine of the class described, the 50 combination with a tank having a bottom wall inclined toward a central outlet aperture, of a belt conveyer mounted to be progressed within said tank and having rotatable supports at the opposite ends of said tank, means to progress said conveyer through said tank, means supporting said conveyer intermediate of the ends of said tank, and operative to prevent sagging, a series of spraying nozzles disposed in parallel relation, transverse to the movement of said conveyer, and having jet apertures, the apertures of the respective adjacent nozzles being arranged to direct sprays radially upon articles carried by said conveyer, and means arranged to draw fluid from the outlet in the bottom of said tank 55 and direct it through said nozzles under pressure.
10. In a machine of the class described, the 60 combination with a tank having its bottom wall inclined from its ends downwardly toward a central outlet aperture, of a belt conveyer mounted to be progressed in said tank, rotatable supports for said conveyer at the opposite ends of said tank, means arranged to progress said conveyer at a predetermined speed, a shelf disposed at the discharge end of said machine, and arranged to receive articles carried by said belt, and automatically discharged therefrom, a series of spraying nozzles disposed 65 in transverse relation to the movement of said belt, and having jet apertures directing sprays radially in spaced parallel planes upon articles carried by said belts, and a centrifugal pump connected with the outlet 70

of said tank, and with said nozzles, and arranged to direct fluid from said tank through said nozzles under pressure.

11. In a machine of the class described, 5 the combination with a conveyer for electro-type molds, of a plurality of parallel spraying nozzles disposed transverse to said conveyer, and arranged to direct elongated sprays in spaced planes parallel with the 10 direction of movement of the conveyer, the

respective sprays of one nozzle being directed between the respective sprays of the other nozzles in overlapping relation.

In witness whereof I have hereunto set my hand this 17th day of November, A. D., 1911.

JAMES F. GOUNLEY.

- 1

It is hereby certified that in Letters Patent No. 1,134,606, granted April 6, 1915, upon the application of James F. Gounley, of Philadelphia, Pennsylvania, for an improvement in "Blackleading-Machines," errors appear in the printed specification requiring correction as follows: Page 1, line 11, for the word "of", second occurrence, read *or*; same page, line 69, for the word "with" read *within*; same page, line 108, for the word "suitable" read *suitably*; page 2, line 29, for the word "contrifugal" read *centrifugal*; page 3, line 34, after the word "relation" insert the word *and*; and that the said Letters Patent should be read with these corrections therein that the same may conform to the record of the case in the Patent Office.

Signed and sealed this 27th day of July, A. D., 1915.

[SEAL.]

R. F. WHITEHEAD,

Acting Commissioner of Patents.
